(57) **CLAIM**

The ornamental design for a display device, as shown and described.

DESCRIPTION

FIGS. 1-7 represent the display device in a folded state according to the present design, in which:

FIG. 1 is a perspective view thereof;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIGS. 8-14 represent the display device in a folded state according to the present design, in which:

FIG. 8 is a perspective view thereof;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

In the drawings, the broken lines illustrate portions of the display device that form no part of the claimed design.

1 Claim, 14 Drawing Sheets
